Primary Examiner — Ricky Pham

(57) **CLAIM**

The ornamental design for a multifunctional electric pressure cooker, as shown and described.

DESCRIPTION

FIG. 1 is a front, top, right side perspective view of a multifunctional electric pressure cooker according to an embodiment;

FIG. 2 is a rear, bottom, left perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The short dash broken lines in the drawings depict portions of the multifunctional electric pressure cooker that form no part of the claimed design.

The shade lines in the figures show contour and not surface ornamentation.

1 Claim, 8 Drawing Sheets
